Patented Apr. 11, 1916.

Fig. 1.

UNITED STATES PATENT OFFICE.

GORDON F. FOWLER, OF OAK PARK, ILLINOIS, ASSIGNOR TO SEARS, ROEBUCK & COMPANY, OF CHICAGO, ILLINOIS, A CORPORATION OF NEW YORK.

OILING-INDICATOR.

1,178,910.

Specification of Letters Patent. Patented Apr. 11, 1916.

Application filed January 24, 1916. Serial No. 73,829.

To all whom it may concern:

Be it known that I, GORDON F. FOWLER, a citizen of the United States, residing at Oak Park, in the county of Cook and State of Illinois, have invented certain new and useful Improvements in Oiling-Indicators, of which the following is a specification.

My invention relates to indicators for oiling system, and has for its object, the provision of simple and efficient means for indicating the operation of oiling systems for machines, such as centrifugal separating machines, and the like.

Other objects will appear hereinafter.

15 An embodiment of my invention is shown in the accompanying drawing forming a part of this specification, and in which,—

Figure 1, is a side elevation of a portion of a centrifugal separator embodying my invention and having portions cut away to expose underlying parts. Fig. 2, is a side elevation of a plate used to close a portion of the casing; and, Fig. 3, is an enlarged fragmental view of a glazed window used in the 25 construction.

In a number of kinds of machines, there are casings which inclose moving parts requiring lubrication. In many of such machines, oil is carried in the bottom of the 30 casing and a rotating wheel, or its equivalent, is mounted in the casing in such a manner as to have its lower edge portion running in the oil. This wheel picks up oil and by means of centrifugal force, throws the oil 35 over the interior of the casing. The oil in being thrown over the interior of the casing, comes in contact with the parts requiring lubrication. In such machines, it is often difficult to determine whether the oil is reaching 40 the bearings and other parts requiring oil in the proper manner, or whether there is foreign matter in the oil. My invention relates to means for indicating whether or not the oil is of proper quality and is being 45 properly distributed in the casing.

Referring more particularly to the drawing, I have shown my invention as applied to a centrifugal separator, such as is used in separating milk and cream. Such a machine, is ordinarily provided with a casing 50 inclosing working parts of the machine. The casing 5, is provided with an elongated opening 6, in one of its vertical sides, through which access is gained to the interior

of the casing. The opening 6, is 55 closed by means of a plate 7, secured to the casing by screws 8. At the upper end of plate 7, is an arm 9, adapted to support a container 10, which holds the liquid to be separated.

In the bottom of the casing 5, is a quantity or pool of oil 11. At the bottom of the casing, is provided a valve 12, for draining the oil 11, from the casing when so desired. From a portion of the valve 12, is a pipe 65 13, which extends upwardly, ending in a curved portion 14, at the desired height of the oil level in the casing. The pipe 13, has its upper end in open communication with the atmosphere, and its lower end in open 70 communication through a part of valve 12, with the oil 11, so that if oil is fed to the bottom of the casing in excess to a quantity substantially as indicated, the excess amount of oil will run over through pipe 13, thereby 75 limiting the height of the oil in the casing. In a convenient position, in plate 7, is fitted a plug 15. The plug is shown as being screw threaded in a portion of the plate 7, but, any other suitable connection may be made 80 when so desired between the plug and plate 7. Oil or other lubricant is inserted in the casing 5, through the opening in which the plug is fitted, when the latter is removed from said opening.

85 The movement of parts of the machine in the casing has a tendency to cause a pressure in the casing above normal atmospheric pressure, and this extra pressure in the casing would tend to drive the oil 11, out 90 through pipe 13. In order to prevent this, vent openings 16, are provided in the plate adjacent the upper portion of the casing 5, which provide an open communication between the outside atmosphere and the interior of the casing.

A separating machine, such as indicated, is usually provided with a wheel 17, which has its lower edge extending into the oil 11. The wheel 17, is fixed on a shaft 18, which 100 is journaled in bearings 19, in casing 5, only one of said bearings 19, being shown. The shaft 18, is connected to a shaft 20, by suitable gearing, not shown, to rotate therewith. The shaft 20, is journaled in bearings 21, in 105 the upper portion of the casing, and provided with a driving means, such as a manually operable crank 22, to impart motion to

the machine. In the operation of the machine, the wheel 17, is adapted to rotate in the direction of the arrow 23, Fig. 1. The oil 11, adheres to the lower portion of the wheel and is carried upwardly until centrifugal force, caused by rotation of the wheel, throws the oil against the interior of the casing. When the oil is thrown against the interior of the casing, it comes in contact with the parts requiring lubrication, and such parts of the oil which are not used, run over the inner sides of the casing back to the pool 11, at the bottom of the basing.

The plate 7, is provided with a recess 24, which provides an unobstructed path for oil to be discharged from the wheel against the filling cap 15. The filling cap 15, is formed hollow with a transparent window fitted in its upper end. With this construction, the oil which is discharged against plug 15, engages window 25, and indicates that the oil is being thrown over the interior of the casing 5, by wheel 17. By providing a window 25, where the oil is continuously thrown against it during the operation of the machine the quality of oil can be determined by simply looking at the window 25. It can also be determined whether or not the proper amount of oil is being distributed over the interior of the casing. Where the oil is being continuously thrown against the glass, the latter is kept clean on its inner side, so that the quantity and quality being distributed in the casing, can be determined at any time by simply looking at the window. In cream and milk separating machines, it often happens that some of these materials get into the casing 5, and are churned up with the oil. As the wheel 17 rotates, the mixture of oil and foreign matter is picked up thereby and by centrifugal force thrown against the window 25, showing the quality of the mixture. It also happens in cold weather that the oil becomes quite thick and will not properly adhere to the wheel 17. In such a case, the oil will not be carried up by the wheel 17 and discharged properly in the casing. Where the oil is too thick to be properly distributed in the casing, very little or none will be shown at the window 25.

While I have illustrated and described the preferred form of my invention, I do not desire to be limited to the precise details set forth, but, desire to avail myself of such variations and changes as come within the scope of the appended claims.

I claim:—

1. In combination, a casing adapted to contain liquid and having a side aperture therein above the liquid level of the casing; a wheel journaled in the casing, the lower portion of the wheel being adapted to engage liquid in the casing; and means connected with the wheel for rotating the latter

to cause said wheel to pick up liquid and discharge the same by centrifugal force into said view aperture.

2. In combination, a casing adapted to contain liquid; a wheel journaled in the casing, the lower portion of the wheel being adapted to run in liquid in the casing; a glazed window in the casing; and means for rotating the wheel causing the latter to pick up liquid and discharge portions of such liquid against the glazed window by centrifugal force.

3. In combination, a casing adapted to contain liquid; means for controlling the height of liquid in the casing; a glazed window in the casing above the liquid level of said casing; a wheel journaled in the casing and having its lower portion extending below the liquid level of said casing; and means for rotating the wheel to pick up liquid and discharge parts of such liquid against the window.

4. In combination, a casing adapted to contain liquid and having an opening in one side; a liquid overflow means in the casing adapted to control the height of liquid in said casing; a wheel journaled in the casing with its lower edge extending below the liquid level of the casing; a plate secured to the casing and closing said opening, the plate having a recess adjacent the wheel; a glazed window in the recess, the wheel upon rotation being adapted to pick up liquid from the casing and throw parts of said liquid through said recess against said window.

5. In combination, a centrifugal separator casing adapted to hold a quantity of oil in its lower portion, one of the vertical sides of the casing having an opening therein above the oil level of said casing; a wheel journaled in the casing and having its lower portion adapted to extend into oil in said casing; a plate covering the opening in the casing; a glazed window in the plate adjacent the wheel, there being a recess in the plate providing a path for oil passing from the wheel to the window when the wheel is being rotated.

6. In combination, a centrifugal separator casing; a glazed window in said casing; and a wheel journaled in the casing adjacent said window and adapted when rotating, to pick up oil from the casing and discharge parts of such oil against said glazed window.

7. In combination, a centrifugal separator casing having a filling opening therein; a filling plug removably secured in the filling opening, the plug being provided with an opening therethrough; and a transparent window closing the outer end of the opening in the plug.

8. In combination, a centrifugal separator casing having a filling opening therein; a filling plug threaded in the filling opening, the plug having an opening extending

therethrough; a transparent window closing the outer end of the plug; and means in the casing adapted to distribute a lubricant over the interior of the casing and against said window.

5 In testimony whereof I have signed my name to this specification, in the presence of

two subscribing witnesses, on this 20th day of January, A. D. 1916.

GORDON F. FOWLER.
